UNITED STATES PATENT OFFICE

152,763

DESIGN FOR A SANDING MACHINE

Kenneth C. Atkin, Muskegon, Mich., assignor to
Clarke Sanding Machine Company, Muskegon,
Mich., a corporation of Michigan

Application April 14, 1948, Serial No. 145,701

Term of patent 14 years

(Cl. D9—2)

To all whom it may concern:

Be it known that I, Kenneth C. Atkin, a citizen of the United States, residing at Muskegon, in the country of Muskegon and State of Michigan, have invented a new, original, and ornamental Design for a Sanding Machine, or which the following is a specification, reference being had to the accompanying drawings, forming a part thereof.

In the drawings:

Fig. 1 is a side elevational view of a sanding machine, showing my new design, the cord portion fragmented for convenience of illustration;

Fig. 2 is a plan view thereof, the cord portion fragmented for convenience of illustration; and

Figure 3 is a front elevational view thereof.

I claim:

The ornamental design for a sanding machine, substantially as shown.

KENNETH C. ATKIN.
